CLAIM

The ornamental design for a dispensing rack for contact lens vials, substantially as shown and described.

DESCRIPTION

FIG. 1 is a front elevational view of a dispensing rack for contact lens vials showing my new design; FIG. 2 is a side elevational view, the side opposite being a mirror image thereof; the contact lens vials being shown in broken lines for illustrative purposes only; FIG. 3 is a top plan view thereof; FIG. 4 is a rear elevational view thereof; and FIG. 5 is a bottom plan view thereof.

FIG. 1.

FIG. 2.

FIG. 3.

FIG. 4.

FIG. 5.
